US00D574830S

(12) **United States Design Patent**
Tasselli et al.

(10) **Patent No.:** US D574,830 S
(45) **Date of Patent:** ** Aug. 12, 2008

(54) **PORTABLE COMPUTER WITH BAR CODE READER**

(75) Inventors: **Corrado Tasselli**, Sala Bolognese (IT); **Monica Alegiani**, Silvi (IT); **Massimo Lotti**, Rimini (IT)

(73) Assignee: **Datalogic, S.p.A.**, Lippo di Calderara di Reno (IT)

(**) Term: **14 Years**

(21) Appl. No.: **29/248,022**

(22) Filed: **Jul. 26, 2006**

(30) **Foreign Application Priority Data**

Jan. 27, 2006 (EM) 000469143-0001

(51) **LOC (8) Cl.** **14-02**

(52) **U.S. Cl.** **D14/426**

(57) **CLAIM**

We claim the ornamental design for a portable computer with barcode reader, as shown and described.

DESCRIPTION

FIG. 1 is a perspective front view of a portable computer with barcode reader according to the present invention.

FIG. 2 is a perspective rear view of the portable computer with barcode reader of FIG. 1.

FIG. 3 is a front view of the portable computer with barcode reader of FIG. 1.

FIG. 4 is a rear view of the portable computer with barcode reader of FIG. 1.

FIG. 5 is a left side view of the portable computer with barcode reader of FIG. 1.

FIG. 6 is a right side view of the portable computer with barcode reader of FIG. 1.

FIG. 7 is a top view of the portable computer with barcode reader of FIG. 1; and,

FIG. 8 is a bottom view of the portable computer with barcode reader of FIG. 1.

1 Claim, 3 Drawing Sheets
